UNITED STATES PATENT OFFICE.

JOSEF HÓRVÁTH, OF STAMFORD, CONNECTICUT.

POWER DEVICE.

Application filed April 27, 1925. Serial No. 26,021.

This invention relates to improvements in compensators for hydraulic turbines which may be run by water from pipes under pressure, such as water mains of water supply systems of cities and towns.

One of the objects of my invention is to obtain a substantially uniform velocity for the turbine of the power plant under variable pressure conditions in the water main 10 by the provision of suitable compensators, which are hereinafter described.

Another object of my invention is to render said compensators sensitive to a very high degree thereby making the uniformity 15 of the motion of the turbine accurate to a very high degree as may be required for driving electrical generators and other machines which require great uniformity of motion.

20 A further object of my invention is to have said compensators comparatively simple, durable and inexpensive.

Other objects and advantages will hereinafter appear.

25 I attain these objects by the compensator illustrated in the accompanying drawings or by mechanical equivalent or obvious modifications of the same.

In the drawings, Fig. 1 is a side elevation 30 of a compensator constructed according to my invention.

Fig. 2 is an enlarged detail view showing sundry details in elevation.

35 Fig. 3 is a fragmentary plan view of one end of my compensator, showing the initial pressure tank and the discharge tank with the auxiliary compensator-cylinder adjacent thereto.

40 Fig. 4 is an enlarged sectional view of a plunger, the cross section being taken on line 4—4 of Figure 1.

Numeral 11 designates the main pressure tank, which is in communication with the water mains 12 of a city water supply system, and it is supplied with a check valve 13 45 to prevent backflow of water therefrom into the water main 12, when the pressure therein is reduced below a certain predetermined level.

50 From the tank 11 a pipe 14 leads to the vertical auxiliary cylinder 15, which is comparatively small in size and which has slidably working therein the piston 16, upon which the lower end of the spring 17 presses; the upper end of said spring 17 abuts against 55 the arm 18 to which it is connected as at 19.

The leakage water from the cylinder 15 above the piston 16 is carried by the pipe 20 to the discharge tray 21, from which it may be carried off to the sewer by means of 60 the drain pipe 22.

From the auxiliary cylinder 15 the water is led through a pipe 23 to the main compensator cylinder 24 which is also vertical as shown and has slidably fitted therein 65 the piston 25, which carries thereon the weight 26.

From the cylinder 24 the water is led through the pipe 27 to the turbine 28; and the discharge from the turbine 28 is delivered through the flexible discharge tube 29 to the elevated chamber 30. The overflow is discharged through pipe 31 to the tray 21.

Sudden variations or fluctuations of pressure in the water from the pressure tank 11 75 are counteracted or compensated for by the elasticity of the spring 17 of cylinder 15, and by the weight of the piston 16.

The pressure tank 11 is provided to act as a reservoir of water for taking care of the 80 operation of turbine 28 during the intervals of time when the pressure in the water main is too low to supply enough water for this purpose.

The main compensator cylinder 24 serves 85 to still further reduce the fluctuations in the water pressure by means of the weight 26, which covers the entire area of the piston 25, and the force developed remains constant during the entire range of positions 90 of said piston 25 in the cylinder 24, the only variation in pressure being due to the changing weight of a variable column of water in said cylinders 24. Check valves 32 and 33 prevent back flow of water from the 95 cylinder 15 to the tank 11 and from the cylinder 24 to the cylinder 15.

The pistons 25 and 16 in their lowest positions engage respectively the stops 34 and 35, to prevent obstruction of the water passages and check valves hereinbefore described by the said pistons 25 and 16.

To compensate for the fluctuation due to the variable head of water in the cylinder 24 I provide a discharge column of variable 105 height by placing the chamber 30 on a vertically slidable support 36, which may act as a plunger sliding in a cylinder 37 or a cross head in a suitable guide, preferably the former.

The lower end of the plunger 36 has connected thereto a roller 38, which rides on the 110

arm 18, which is actuated by the piston 16, to which said arm 18 is connected.

In this way the descent of piston 16, which takes place when the column of water in the cylinders 15 and 24 are falling to a lower level, automatically causes the plunger 36 with the chamber 30 to descend, thereby reducing the height of the column of water in the discharge pipe 29 and thereby reducing the back pressure on the turbine 28 to the same extent that the pressure of the water in the pipe 27 has been reduced by the falling of the water in the cylinders 15 and 24 was reduced.

15 The cylinder of guide 37 may be so located with relation to the cylinder 15 as to make the variation of the level of the water in the chamber 30 exactly equal to the variation of the level of the water in the cylinder 24, if desired. The motions of pistons 16 and 25 are related to each other. For illustrative purposes, assume the pressure in tank 11 to fall. Immediately check valve 32 closes. The turbine 28 continues to draw water from cylinder 24 causing a fall in pressure and a corresponding fall in piston 25. A fall in pressure in cylinder 24 is immediately communicated to cylinder 15 through the connecting pipe 23, and the piston 16 is caused to fall. When the pressure in cylinder 15 reaches the new reduced pressure in tank 11, the check valve 32 permits a flow of water. But when the piston 16 descended, the lever 18 correspondingly descended, lowering the chamber 30 so as to reduce the exhaust resistance of the turbine 28, thereby unaffecteding the running of the turbine, even though the entrance pressure was reduced. Similarly had the pressure increased in tank 11, the piston 16 would ascend, and so would the piston 25. But the ascending piston 16 causes the lever 18 to raise, thus raising the chamber 30, and adding to the exhaust resistance of the turbine, which addition counteract the increased inlet pressure of the turbine, thereby having no affect as to the running of the turbine. It should be noticed that check valve 33 functions to arrest the backflow of water from cylinder 24 to 15, so that a change in pressure of tank 11, and possibly cylinder 15, is drawn off by the turbine, instead of permitting backflowing to equalize said change.

55 The discharge tube 31 may be flexible if desired or part of it may be flexible at 39. The arm 18 is pivotally connected at 40 to the post 41, and lowers the piston 16 with the spring 17 when it swings downwardly; the piston within the two cylinders 16 and 25 in this way reach their lowest positions at about the same time.

60 The leakage from the cylinder 24 past the piston 25 may be carried off by means of the pipe 42 to the tray 21.

65 As illustrated in Figure 4, the plunger 36

carries at its upper end a movable plate 43 having a valve seat 44 in approximately its centre. The plate 43 is guided by the rods 45, 46 about which springs 47, 48 are wound resting with their lower ends in plate 43 and 70 engaging with their upper ends a plate 49. The plate 49 carries a valve 50 adapted to engage the valve seat 44.

By the above described arrangement and by making the cylinder 24 of adequate size, 75 the pressure of water acting on the turbine will be uniform to a very high degree of exactness for a considerable fluctuation in the pressure of the water in the tank 11 or in the mains which supply the same.

80 An air chamber 51 may be provided for the tank 11, if desired.

Having thus described my invention what I claim as new and desire to protect by Letters Patent of the United States is as follows:

1. In a device of the class described the combination of a turbine, an accumulator connected to the turbine inlet, a cylinder, a check valve controlled water inlet to said cylinder, a check valve controlled water connection from said cylinder to said accumulator, a piston slidable in said cylinder, a rod connected to said piston, a pivoted lever engaged by said rod, and means for varying 90 the exhaust resistance of said turbine, said means being operated by said lever.

2. In a device of the class described the combination of a turbine, an accumulator connected to the turbine inlet, a cylinder, a 100 check valve controlled hydraulic cylinder, a connection from said cylinder to said accumulator, a piston slidable in said cylinder, a rod connected to said piston, a pivoted lever engaged by said rod, and means for varying 105 the exhaust resistance of said turbine, said means being operated by said lever.

3. In a device of the class described the combination of a turbine, an accumulator connected to the turbine inlet, a cylinder, a 110 check valve controlled water inlet to said cylinder, a check valve controlled water connection from said cylinder to said accumulator, a piston slidable in said cylinder, a rod connected to said piston, a pivoted lever engaged by said rod, and means for varying 115 the exhaust resistance of said turbine, said means being operated by said lever, and characterized by a plunger having a roller at its lower end engaging said pivoted lever, 120 a chamber fixed to the upper end of said plunger, said chamber having a valve opening on its upper face, a valve head engageable with said valve opening, a flexible connection between the turbine exhaust and said 125 chamber, and another connection from said valve opening to a drain device.

In testimony whereof I have affixed my signature.

JOSEF HÖRVÁTH.
